FIG. 2

UNITED STATES PATENT OFFICE

2,618,895

GRAVITY OPERATED TOY

Clayton E. Sidney, Milwaukee, Wis.

Application March 1, 1949, Serial No. 78,973

4 Claims. (Cl. 46—130)

1

This invention relates to a gravity-operated toy.

A toy embodying the present invention operates on the same general principle as the toys which walk down an incline. However, it is the object of the present invention to provide a toy which hangs by its hands from an overhead support and swings from side to side, the weight of the toy causing it to act like a pendulum to transfer its weight from one hand to the other, and the hands and arms being so designed as to be gravity-operated to advanced positions each time the hand is relieved of the weight of the figure.

More specific objects will appear from the following disclosure of the invention, and reference to the accompanying drawings, wherein:

Fig. 1 is a view in side elevation of a toy embodying the invention.

Fig. 2 is an enlarged view of the toy as viewed in front elevation, the overhead support being shown in section.

Fig. 3 is a detail view fragmentarily illustrating the toy in perspective.

There is an overhead support at 4 which may take the form of a thin and relatively narrow strip of wood having its end 5 free, and its end 6 engaged in the upper end of a standard 7 erected on a base at 8.

The toy figure 9 has been selected, for purposes of illustration, to represent a monkey. To induce added movement, its legs 10, 11 may be pivoted at 12 to the body 13, although the legs do not contribute to the operation of the figure down the incline support 4.

The arms 14, 15 are also pivoted at 16 to the body 13. The movement permitted the arms is desirably limited by a cross pin 17 which projects at both sides of the body to provide stop means against which the arms engage at their permissible limit of oscillation.

At least at their upper ends, the arms 14, 15 have clearance sufficient to receive the supporting strip 4 between them. For suspending the figure from the support, the respective arms are provided with inwardly projecting fingers 18, 19 resting on the upper surface of the supporting strip 4. This surface is desirably roughened as indicated at 20 in Fig. 3. The roughening need not be applied by any special machinery, it being sufficient merely to avoid planing the top surface of the wooden strip.

When either of the arms is relieved of the weight of the figure, it tends to fall by gravity about its fulcrum 16 to the full extent permitted

2

by the stop pin 17. This happens on each occasion when the figure swings from side to side in pendular movement, such as occurs during the use of the toy. Figs. 1 and 3 show the toy in a position where the body of the device has swung toward the observer, thus imposing the entire weight temporarily on the finger 18 of arm 14, and leaving the finger 19 free of the support 4. The drawings show the arm in the position to which it has dropped in consequence of being relieved of the weight of the body.

As the toy swings back away from the observer, the weight of the body will be transferred to the finger 19 of arm 14, thus relieving the finger 18 of load. Since the body has its center of gravity well at the rear of finger 19, this will cause the body to move forwardly toward a position beneath finger 19. This immediately relieves finger 18 and lifts it above the level of the supporting strip 4, whereupon it, in turn, will move forwardly by reason of the gravity-induced downward movement of its arm 14 about its pivotal connection with the body.

The resulting movement of the body is not only forward but lateral closely simulating the movements of a person swinging from an overhead ladder or other support and moving hand-over-hand longitudinally thereof. As the lateral swinging movement of the animal transfers the weight of its body from one finger to the other, the high finger is relieved of weight and swings downwardly, only to receive the weight of the body again when the body swings in the opposite direction with the pendular movement above described.

The fact that the support 4 has a free end facilitates the replacement of the toy upon the support after it has dropped from the free end thereof.

40 I claim:

1. The combination with an overhead support having lateral dimension and a longitudinal inclination, of a body depending from said support and provided with laterally spaced forwardly extending arms in pivotal connection with the body and provided with laterally projecting fingers engaged with the support at laterally offset points thereon, the body being adapted for pendular lateral movement respecting the support, in the course of which movement the fingers are alternately relieved of weight and permitted to swing downwardly along the support to a new position for receiving the weight of the body in the opposite pendular movement thereof, said support having laterally spaced margins defining guide

paths for the arms in their swinging movement.

2. A toy comprising the combination with a longitudinally inclined overhead support having lateral dimensions, of a depending figure comprising a body beneath the support, a pair of laterally spaced arms individually pivoted to the body for oscillatory movement with respect thereto, each of said arms extending forwardly and thence upwardly from its pivotal connection with the body, stop means limiting the oscillation of the respective arms forwardly and downwardly about their pivotal connections with the body, and fingers connected with the respective arms and extending oppositely over the spaced margins of the overhead support into positions for engagement with the upper surface thereof, the said figure being adapted for lateral pendular movement respecting the support, in the course of which movement the fingers are alternately relieved of the weight of said body and permitted independent oscillatory movement downwardly of said support to a new position for receiving the weight of the body in the opposite pendular movement thereof, said support having laterally spaced margins defining guide paths for the arms in their oscillatory movement.

3. The device of claim 2 in further combination with a base and a standard with which only one end of said overhead support is connected, the other end of said overhead support being free.

4. A toy comprising a body having laterally

spaced upwardly extending arms provided with transverse pintles upon which the arms are pivoted to the body for front-to-rear oscillation respecting the body, the arms and body having means limiting oscillation of the arms respecting the body and the body being suspended by said arms for lateral oscillation unitarily therewith, the respective arms having projecting fingers offset laterally from each other and an overhead support having lateral dimension, the spaced margins of said support comprising mutually offset paths guiding the arms in their oscillatory movement and alternately supporting the body as the weight of the body is transferred from one finger to another in pendular lateral oscillation of the body respecting the support, whereby to permit successive oscillatory forward movement of the arms along the respective paths as their respective fingers are relieved of weight.
